UNITED STATES PATENT OFFICE.

WADE H. WINEMAN, OF CHICAGO, ILLINOIS, ASSIGNOR TO SULLIVAN MACHINERY COMPANY, A CORPORATION OF MASSACHUSETTS.

COMPRESSOR-CONTROLLING MECHANISM.

1,398,912.

Specification of Letters Patent. Patented Nov. 29, 1921.

Application filed December 22, 1917. Serial No. 208,432.

To all whom it may concern:

Be it known that I, WADE H. WINEMAN, a citizen of the United States, residing at Chicago, in the county of Cook and State of Illinois, have invented certain new and useful Improvements in Compressor-Controlling Mechanisms, of which the following is a full, clear, and exact specification.

My invention relates to compressor controlling mechanisms.

It has for its object to provide an improved automatically acting controlling mechanism for compressors, especially adapted to use in connection with motor driven compressors. A further object of my invention is to provide an improved controlling mechanism for motor driven compressors wherein the compressor is loaded and unloaded automatically in the desired sequence in accordance with variations in terminal pressure, and wherein the compressor driving motor is automatically started and stopped in such a manner that the latter is enabled to be brought up to speed prior to the loading of the compressor, or is disconnected from the circuit after the compressor has been unloaded. A further object of my invention is to provide improved and simplified controlling mechanism for the compressor and for the motor circuit, adapted to be controlled by the terminal pressure and responsive to variations therein whereby the above ends may be attained. These and other objects and advantages of my improvement will, however, hereinafter more fully appear.

In the accompanying drawings, I have shown for purposes of illustration one embodiment which my invention may assume in practice, although it will be understood that my invention is not limited to embodiment in the form here illustrated.

In these drawings,—

Figure 1 is a side elevation of a complete motor driven compressor equipped with my improvement, the compressor cylinder being broken away to show the pistons therein.

Fig. 2 is a detail sectional view showing the unloading valve and the controlling mechanism for the same and the motor switch.

Fig. 3 is a plan view of the mechanism shown in Fig. 2, with parts omitted.

Fig. 4 is a detail plan view of the switch mechanism.

Fig. 5 is a side elevation of the switch mechanism.

In this illustrative construction, I have shown a compressor of a well known multi-stage type including a frame 1 having a low pressure cylinder 2 and a high pressure cylinder 3 in which pistons 4 and 5 are reciprocable in a well known manner by the compressor crank shaft 6, which, as shown, is adapted to be rotated by means of a pulley 7 from a suitable motor 8, as for instance through a belt connection 9. As usual in such a compressor, the latter is provided with an intercooler 10 connected between the low and high pressure cylinders, and with a receiver 11 connected to the high pressure cylinder through a suitable connection 12. It will also be observed that, as in a usual construction, an unloading valve is provided to control the flow of air through the intake 13 leading to the low pressure cylinder, and thus control the loading and unloading of the compressor.

More specifically, it will be noted that in this illustrative construction this unloading valve, indicated at 14, is adapted to be raised from or lowered into its seat in apertures 15 in a suitable unloading valve casing 16 to open or close the intake. As shown, this unloading valve 14 is of the normally open type and adapted to be raised from its seat by springs 17 connected between a part hereinafter described movable with the same and the usual transversely disposed spring arms 18 disposed at the top of the valve casing. In my improved construction, this valve is also slidably mounted above a projection or nut 19 on the lower end of an elongated rod 20 which extends up through the top of the unloading valve casing, and is provided at its upper end with a piston 21 movable in a suitable cylinder 22 having its lower end open to the atmosphere.

In a preferred form, the upper end of this cylinder 22 is connected through a pipe connection 23 with a pressure responsive valve 100 of any suitable type responsive to variations in receiver pressure, herein shown as of a well known type, and illustrated in simplified form in Fig. 2 as comprising a valve

casing 24 having a piston 25 movable therein and having thereon a tapered valve member 26 adapted to close or open an aperture 27 and thus control the communication between 5 a pipe 28 connected to the receiver and the pipe 23 leading to the cylinder 22. As usual in such a construction, the piston 25 is normally held closed by a spring 29, the tension of which is adjustable by means of the adjustment of a removable cap 30, and a vent 31 is supplied in the bottom of the valve casing at a point below the opening 27 so that when a drop in receiver pressure permits the valve 26 to close, the air in the 10 cylinder 22 and above the piston 21 may escape to the atmosphere.

As shown, the valve rod 20 preferably also has rigidly connected thereto at a point beneath the same a cross arm 32, preferably 20 freely movable vertically in vertical slots 33 disposed between the cylinder 22 and the unloader valve casing 16. In a preferred form, this cross arm 32 is also connected to the lower ends of the spring 17 and also to a 25 suitable retarding means. This means is, for example, herein shown to include an upwardly and laterally disposed extension 34 thereon, which is freely slidable downward along a rod 36 which is provided, in 30 turn, at its top with a stop member 35 and at its bottom is connected to a dashpot piston which slides in a suitable dashpot casing 38. As usual in such constructions, this dashpot piston 37 is also provided with a 35 suitable hole 39 therein to enable the fluid contained in the casing 38 to pass through the piston and thus enable the latter to be slowly moved back and forth to its various positions. It will be evident that its weight 40 will cause the dashpot piston to move downward in its cylinder when it is not supported by the extension 34 and so that as the extension moves upward again after closure of the 45 valve 26, the extension having engaged the stop member 35 will be forced to drag the dashpot piston upward with it and so will effect the desired delay between closure of the switch later described and reloading of the compressor.

50 Operatively associated with the cross arm 32 and actuated thereby, is the circuit controlling mechanism of the motor 8. This mechanism may obviously assume the form of any suitable switch, though preferably a 55 switch of the snap switch type is utilized. Herein, it will be noted that a snap switch of a well known Cutler-Hammer type is employed. As shown, this switch includes a switch actuating member 40 pivoted at one 60 end at 41 on a suitable upstanding support, and normally pressed upward by means of a coiled spring 42 so that a lug 43 thereon is directly in the path of the free end of the cross arm 32. As shown, this switch actuating member 40 is also provided with a down-

wardly disposed lug or extension 44 on its front end, which is in turn adapted to be moved downward through a suitable slot 45 in a pivoted spring controlled contact carrying member 46, and into engagement 70 with the tail of a spring pressed bell-crank latch 47 to release the same from engagement with the edge of the slot 45 and thus enable the contact carrying member under the action of a biased spring 48 to break the circuit through the conductors 49 and 50 leading to the motor 8. Thus, it will be noted that as the cross arm 32 is moved up and down, the circuit connections of the motor 8 are automatically changed, the circuit of 80 the same remaining closed while the cross arm 32 is elevated, and being automatically opened when that arm engages with the member 40, thus timing the operation of the switch in accordance with the movement of 85 the unloading valve.

In the operation of my improved construction, the parts will occupy the position shown in Fig. 2 when the compressor is loaded and driven by the motor. When, 90 however, the pressure in the receiver 11 rises to a predetermined amount, dependent upon the position of the cap 30, the same will then act upon the piston 25 of the pressure controlling valve in such a manner as to 95 cause that piston and its valve 26 to move upward in its cylinder 24 against the pressure of the spring 29 and thus permit the pressure to flow from the pipe 28 through the opening 27 and into the pipe 23 and the 100 cylinder 22, and act upon the top of the piston 21 in such a manner as to depress the same and thus lower the cross arm 32. During the first part of the downward movement of this cross arm, it will be observed that the unloading valve 14 will move downward therewith, i. e. until this valve 14 engages with its seat. When this occurs, however, the movement of the valve will be arrested and, through the sliding connection existing between the valve and its rod 20, the latter will thereafter move independently. For instance, referring to Fig. 2, it will be noted that when the cross arm 32 reaches the upper dotted line position shown, the movement of the valve 14 will be arrested, the latter at that time having reached its seat and closed the intake 13 in such a manner as to unload the compressor. However, as the cross arm 32 continues to move downward toward the lower dotted line position thereof, it will be observed that the end of the cross arm 32 will engage with the lug 43 on the switch actuating member 40 in such a manner as to 110 depress the same and cause the latch member 47 to be released and to release the contact carrying member 46 which under the influence of its spring then opens the motor circuit. Conversely, with the parts thus at 115 120 125 130

rest and the compressor unloaded, when the pressure in the receiver 11 falls below a pre-determined amount, likewise determined by the position of the cap 30, the valve 26 will 5 then close and thus enable the pressure above the piston 21 to be exhausted to the atmosphere through the vent 31. Consequently, the valve rod 20 will then be free to move upward under the influence of the un-loader valve springs 17 in such a manner as 10 to raise the cross arm 32 from engagement with the lug 43 on the member 40 and thus release the automatically closing switch, which then automatically moves its contact carrying member 46 to circuit closing position and starts the motor in operation. This, it will be noted, however, occurs prior 15 to the loading of the compressor, as, due to the sliding connection between the unloading valve 14 and its rod 20, the latter will have thus far moved independently of the unloading valve. However, when the cross arm 32 under the drag of the dash pot 37, 38 does occupy the upper dotted line position shown in Fig. 2, the rod 20 will then 20 pick up the unloading valve 14 and lift the same from its seat in such a manner as to load the compressor. Thus, it will be noted that an appreciable time interval is introduced 25 between the closing of the motor circuit and the loading of the compressor, which interval is amply sufficient to enable the motor to be brought up to speed.

As a result of my improvement, it will 30 be observed that a mechanism is produced in which the desired sequence of operation of the compressor unloading mechanism and the motor circuit controlling mechanism is automatically maintained with absolute cer- 35 tainty, the several mechanisms being operated in direct accordance with the variations between any desired limits of the pressure in the receiver. It will also be evident that, through the use of my improved mechanism, it is rendered entirely unnecessary to provide any electrical equipment other than a simple snap switch, the entire control being effected through the use of 40 an exceedingly simple and rugged mechan- 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860

from its spirit or the scope of the appended claims.

What I claim as new and desire to secure by Letters Patent is:

1. In a compressor controlling apparatus, 70 a plurality of controlling mechanisms for controlling the operation of a compressor, and means for governing the operation of both said controlling mechanisms normally disengaged from one of the latter but en- 75 gageable therewith to control the same.

2. In a compressor controlling apparatus, 80 a plurality of controlling means for controlling the operation of a compressor, pressure actuated means for operating said plurality of controlling means, and a plurality of retarding means for controlling the operation of said operating means.

3. In a compressor controlling apparatus, 85 a plurality of controlling means for controlling the operation of a compressor, a single pressure actuated means for operating said plurality of controlling means, and separate means connecting said operating means and said plurality of controlling means. 90

4. In a compressor controlling apparatus, 95 a plurality of controlling means for controlling the operation of a compressor, and means alternately engageable with said controlling means to actuate the latter.

5. The combination with a motor driven compressor, of an unloading mechanism, a motor controlling mechanism, means movable in opposite directions to cause loading and unloading operation of said unloading 100 mechanism and starting and stopping operation of said motor controlling mechanism, and means for controlling said last named means.

6. The combination with a motor driven 105 compressor, of an unloading mechanism, a motor controlling mechanism, means movable in opposite directions to cause loading and unloading operation of said unloading mechanism and starting and stopping operation of said motor controlling mechanism, and a pilot valve for controlling said last named means.

7. In a compressor controlling mechanism, 110 unloading mechanism comprising, in combination, a fluid pressure controlled intake controlling valve, a controlling valve therefor responsive to variations in terminal pressure and controlling the supply of operating fluid for said fluid pressure controlled intake controlling valve, means for permitting discharge of said fluid at a rate less than its rate of supply, and means for retarding movement of said intake controlling valve toward loading position. 115

8. In a compressor controlling mechanism, 120 an intake controlling valve, means for effecting alternate opening and closing thereof including a controlling valve therefor responsive to variations in terminal pres- 125

- sure, and separate means yieldably resisting movement of said intake controlling valve toward loading position and operative to retard such movement.
- 5 9. In a compressor controlling mechanism, unloading mechanism comprising, in combination, an intake controlling valve, fluid pressure means for controlling the operation thereof including a controlling valve responsive to variations in terminal pressure, and coöperating means independent of said fluid pressure means operative to retard movement of said intake controlling valve toward loading position.
- 10 10. In a compressor controlling mechanism, the combination comprising an unloading valve, and circuit controlling mechanism responsive to variations in terminal pressure and including a member movable 20 with said valve and independently thereof.
- 15 11. In a compressor controlling mechanism, the combination comprising intake valve mechanism, a motor controlling switch independent thereof, and a single actuating member for said elements movable in response to variations in terminal pressure.
- 25 12. In a compressor controlling mechanism, the combination comprising intake valve mechanism, a motor controlling switch, and a single actuating member for 30 said elements movable in response to variations in terminal pressure to successively actuate the same through separate connections therewith.
- 35 13. In a compressor controlling mechanism, the combination comprising a valve responsive to variations in terminal pressure, a cylinder receiving fluid therefrom, a normally retracted piston in said cylinder, 40 and circuit controlling mechanism controllable by said piston through a lost motion connection.
- 45 14. In a compressor controlling mechanism, the combination comprising a valve responsive to variations in terminal pressure, a cylinder receiving fluid therefrom, a piston in said cylinder, and circuit controlling mechanism controllable by said piston when 50 said compressor is unloaded.
- 55 15. In a compressor controlling mechanism, the combination comprising unloading valve mechanism responsive to variations in terminal pressure, motor circuit controlling mechanism controlled thereby, and coöperating means for inserting an appreciable interval between the closure of the motor circuit and the loading of the compressor.
- 60 16. In a compressor controlling mechanism, the combination comprising an intake controlling valve, a controlling valve therefor responsive to terminal pressure, and motor circuit controlling mechanism including a member movable with or independently of said intake controlling valve.
- 65 17. In a compressor controlling mecha-
- nism, the combination comprising a pressure actuated valve responsive to variations in terminal pressure, a movable member controlled thereby, motor circuit controlling mechanism engageable by said member, and 70 retarding means operatively connected to said member.
18. In a compressor controlling mechanism, the combination comprising a pressure actuated valve responsive to variations in 75 terminal pressure, a movable member controlled thereby, motor circuit controlling means engageable by said member, and automatically acting means for retarding the movement of said member. 80
19. In a compressor controlling mechanism, the combination comprising a pressure actuated valve responsive to variations in terminal pressure, a movable member controlled thereby, motor circuit controlling 85 means engageable by said member but normally disengaged therefrom, and automatically acting means for retarding the movement of said member.
20. In a compressor controlling mechanism, the combination comprising unloading valve mechanism responsive to variations in terminal pressure, motor circuit controlling mechanism, and means movable upon a decrease in terminal pressure to close said circuit connections and after an appreciable 90 interval load the compressor. 95
21. In a compressor controlling mechanism, the combination comprising a valve responsive to terminal pressure, means controlling the supply of fluid through the inlet of the compressor, and means controlled by said valve for closing the motor circuit and after an appreciable interval opening the compressor inlet. 100 105
22. In a compressor controlling mechanism, the combination comprising an unloading valve, operative connections therefor responsive to variations in terminal pressure including a member movable to actuate said 110 valve or movable independently thereof, and motor circuit controlling means controlled by said member.
23. In a controlling mechanism for a motor driven compressor system, the combination comprising a valve responsive to a drop in terminal pressure, pressure fluid actuated means controlled thereby controlling the circuit connections of the compressor driving motor, and means for loading the 115 compressor only after closure of said motor circuit. 120
24. In a compressor controlling mechanism, the combination comprising a pressure actuated valve responsive to variations in 125 terminal pressure, a movable member controlled thereby, motor circuit controlling mechanism engageable by said member, and retarding means operative to retard movement of said member in one direction. 130

25. In a compressor controlling mechanism, the combination comprising a valve responsive to variations in terminal pressure, a movable member controlled thereby, resilient means normally resisting movement of said member, circuit controlling means engageable by said member, and retarding means coöperating with said member. 5
- 10 26. In a compressor controlling mechanism, the combination comprising a valve responsive to variations in terminal pressure, a movable member controlled thereby, resilient means normally resisting movement of said member, circuit controlling means engaged by said member, and means for retarding said member as the same is moved in one direction. 15
- 20 27. In a compressor controlling mechanism, the combination comprising a movable member responsive to variations in terminal pressure, resilient means normally resisting movement of said member, circuit controlling means actuated by said member, and means for retarding the movement of said member. 25
- 30 28. In a compressor controlling mechanism, the combination comprising a member movable in response to variations in terminal pressure, motor circuit controlling mechanism controlled thereby, resilient means normally opposing movement of said member, and means effective to retard the movement thereof in one direction. 35
- 40 29. In a compressor controlling mechanism, the combination comprising a member movable in response to variations in terminal pressure, motor circuit controlling mechanism actuated thereby, resilient means normally opposing movement of said member, and means effective to retard the movement after actuation of said motor controlling means. 45
- 45 30. In a compressor controlling mechanism, the combination comprising a movable member responsive to variations in terminal pressure, motor circuit controlling mechanism controlled thereby, means normally opposing movement of said member, and means whereby said member is caused to move freely in one direction and relatively slowly in the opposite direction. 50
- 55 31. In a compressor controlling mechanism, the combination comprising a member movable in response to variations in terminal pressure, a snap switch actuated by said member but normally disengaged therefrom, an unloading valve, and means for inserting a substantial interval between the closure of said switch and the opening of said unloader valve. 60
- 60 32. In a compressor controlling mechanism, the combination comprising a normally inoperative member movable in response to variations in terminal pressure, an unloader valve slidably connected thereto, circuit controlling connections controlled by said member, and means for delaying the movement of said member in one direction. 65
- 70 33. In a compressor controlling mechanism, the combination comprising a member movable in response to variations in terminal pressure, resilient means resisting movement thereof, circuit controlling mechanism actuated by said member, means for delaying the movement of said member in one direction, and an unloader valve movable with said member. 75
- 80 34. In a compressor controlling mechanism, the combination comprising a normally inoperative member movable in response to variations in terminal pressure, an unloader valve slidably connected thereto, circuit controlling connections controlled by said member, and retarding means slidably connected to said member. 85
- 90 35. In a compressor controlling mechanism, the combination comprising a member movable in response to variations in terminal pressure, resilient means resisting movement thereof, circuit controlling mechanism actuated by said member, means for delaying the movement of said member in one direction, and an unloader valve slidably connected to said member. 95
- 100 36. In a compressor controlling mechanism, the combination comprising a valve responsive to variations in terminal pressure, a cylinder communicating therewith, a piston in said cylinder, a rod connected to said piston, resilient means resisting movement of said piston in one direction, circuit controlling connections controlled by said rod, and retarding means for retarding the movement of said piston in one direction. 105
- 110 37. In a compressor controlling mechanism, the combination comprising a valve responsive to variations in terminal pressure, a cylinder, a piston therein receiving pressure fluid from said valve, a rod connected to said piston, an unloader valve slidably connected to said rod, a resilient connection resisting movement of said rod in one direction, circuit controlling mechanism controlled by said rod, and a dash pot 115 having a sliding connection between its piston and said rod. 115
- 120 38. In a compressor controlling mechanism, the combination comprising a valve responsive to variations in terminal pressure, a cylinder communicating therewith, a piston in said cylinder, a rod connected to said piston, resilient means resisting movement of said piston in one direction, circuit controlling connections actuated upon movement of said rod, and retarding means for retarding the movement of said rod after disengagement thereof from said circuit controlling mechanism. 125
- 130 39. In a compressor controlling mechanism, the combination comprising a valve responsive to variations in terminal pressure, an

nism, the combination comprising a valve responsive to variations in terminal pressure, a cylinder communicating therewith, a piston in said cylinder, a rod connected to said 5 piston, resilient means resisting movement of said piston in one direction, circuit controlling mechanism operable to close the circuit upon movement of said piston in one direction and to open the same upon a 10 reverse movement thereof, and retarding means effective to delay further movement of said piston after the circuit is opened.

40. In a compressor controlling apparatus, in combination, a plurality of controlling 15 means for controlling the operation of the compressor, a single actuating means for said first mentioned means, said last mentioned means having substantially unretarded movement in one direction and a de- 20 layed movement in the other.

41. In a compressor controlling apparatus, in combination, a plurality of controlling means for controlling the operation of the compressor, a single actuating means for 25 said first mentioned means, said means being adapted to operate said controlling means in one direction of movement without material interval and in the other direction at distinctly separated intervals.

42. In combination with a compressor, a 30 motor drive therefor, and controlling mechanism for the system comprising an unloading mechanism having means operative in different positions thereof to effect the load- 35 ing and unloading of the compressor, a controlling mechanism for said motor drive comprising means operable in different positions thereof to stop or start the driving of the compressor, and a single member co- 40 operating with both of said first means for separately actuating them.

43. In combination with a compressor, a motor drive therefor, and controlling mechanism for the system comprising an unload- 45

ing mechanism having means operable in 45 different positions thereof to effect the loading and unloading of the compressor, a controlling mechanism for said motor drive comprising means operable in different positions thereof to stop or start the driving of 50 the compressor, and means coöperating with both of said first means for separately actuating them, said last mentioned means having coöperating therewith a retarding means effective to insert a predetermined delay be- 55 tween operations of said first two means.

44. In a compressor controlling mechanism, in combination, a switch, a controlling valve, means for successively actuating the same including a cylinder and piston co- 60 operating with each of said elements, and means for delaying movement of said piston in said cylinder.

45. In a motor driven compressor controlling system, the combination comprising 65 compressor unloading mechanism and motor controlling mechanism, and means comprising a single member operative to control said mechanisms at distinctly different instants.

46. In a motor driven compressor controlling system, the combination comprising compressor unloading mechanism and motor controlling mechanism, and means comprising a single member operative to 75 control both of said mechanisms but providing a predetermined delay between the operations thereof.

47. In a controlling mechanism for a motor driven compressor system, in combination, a switch mechanism, a controlling valve mechanism, and controlling means for 80 said switch and valve mechanisms comprising a single member operative upon movement to control said mechanisms at different 85 points in its path.

In testimony whereof I affix my signature.

WADE H. WINEMAN.
